PRINTED SHEET DRIER

Eldo M. Jump, Toledo, Ohio

Application June 16, 1934, Serial No. 730,947

4 Claims. (Cl. 34—18)

This invention relates to handling of sheet material.

This invention has utility when incorporated in driers for paper sheets from printing presses and to promote regularity in stacking, due to 5 minimizing the disturbance from static electricity.

Referring to the drawing:

Fig. 1 is a side elevation, with parts broken 10 away, of an embodiment of the invention at the delivery of a reciprocating bed type of printing press;

Fig. 2 is a plan view of the device, with parts broken away;

15 Fig. 3 is a section on the line III—III, Fig. 2; Fig. 4 is a section on the line IV—IV, Fig. 2; Fig. 5 is a section on the line V—V, Fig. 2; and Fig. 6 is a perspective view of a flanged split ring clamp to serve as a shield.

20 Printing press roll 1 is shown as having drive 2 therefrom for lower or supporting endless tapes or conveyors 3. From this gear train 2, gear train 4 extends to drive upper opposing hold-down tapes or guard strings 5. The gear trains 2, 4, as 25 well as the tapes are mounted in frame 6 on shaft 7 as an axis and have side rails 8. The printed sheet from the roll 1 is directed by fingers 9 to travel between the tapes 3, 5, for delivery to table 10. The several tapes 3, as well as the tapes 5, 30 are transversely adjustable for the desired spacing in the paper width. It is usual to conduct the printed sheet centrally between the bars 8 and space the supporting upper reach of the tapes 3 to carry the printed sheet with opposing tapes 5 having lower reaches to hold the sheet in 35 position on the supporting traveling tapes.

The opposing reaches, that is, the upper reaches of the tapes 3 and the lower reaches of the tapes 5, travel in the common direction away from the 40 roll 1 and at a common speed.

In accordance with the invention herein, U-brackets 11, 12, are seated on the respective rails 8. Set screws 13 at these brackets may be operated to grip the respective rails 8 and thus 45 hold the brackets 11, 12, from shifting. It is thus a simple matter to locate this device and determine the spacing thereof from the printing roll 1. The spacing may be at a greater distance from the roll 1 as the speed of the machine is greater. 50 The bracket 11 carries nipple 14 to a T fitting 15. Flexible fuel supply as gas hose 16 connects to this T fitting 15 and therefrom this fuel supply may flow by duct 17 to fitting 18 at the bracket 12, thereby providing cut-off cock 19 at 55 the front or operator side of the printing press

so that the cutting off of the supply of gas may readily occur while the supply line 16 is not in a cluttering position for the access of the operator to the printing bed as the delivery is tilted upward on the axis shaft 7 and held in such upwardly set position by strut 20.

From this valve 19 the supply gas may flow into tube 21 parallel with the duct 17 and also extending between the brackets 11, 12, and having blank ends at such brackets. This duct or pipe 21 on its upper side toward the supporting reaches of the tapes 3 has transversely of such series of tapes, series of minute openings 22. In practice, with natural gas, these openings are not of sufficient size to permit insertion of a pin point therethrough. As the supply of fuel is to this pipe 21, escaping gas from these ports or jets 22 may be lighted to provide flames 23, desirably of a height not to reach paper sheet 24 as carried by the tapes 3.

Embracing this tube 21 and of a number corresponding with the sets of tapes 3 are split sleeves 25 having connection by pins 26 to collars 27. In these collars 27 set screws 28 coact as set up to anchor the sleeves 25 as shields over jets or ports 22. It is thus convenient for the pressman, as he is locating the tapes 3, 5, likewise to back off the set screws 28 and in register with such tapes locate the sleeves 25. As so located, these set screws 28 may be tightened and the 30 ports 22 in the region which would allow the flames 23 to attack the tapes 3 are thus obscured or cut out. In practice this gas jet burner type of drier coacts with the freshly printed sheet, even in the rapid delivery operations, to contribute to the drying of the ink but additionally there is efficiency, whether due to ionizing action of static electrical charge from frictional source on the paper sheet promoted by atmospheric 35 conditions, or grounding effectiveness due to conductivity through the heated zone.

There is accordingly met in practice such elimination of static electricity disturbances that the sheets will move without clinging or fluttering and deposit with regularity in a symmetrical 45 stack upon the table 10. This operation is of course a feature of great convenience to the pressman, in that there is minimized the occasion for stopping the press to adjust clogged sheets in the delivery. There is the symmetrical stack 50 which reduces the labor in disposal. While in an emergency the pressman may cut off the gas supply to extinguish the flames, there is in the normal operation rare occasion so to do, for the burner, even upon stoppage of the press, does 55

not attack the tapes with the set up as designed herein. Furthermore, there is, due to the shortness of the jet, not an immediate attack for igniting the paper should the machine merely stop for a brief interval.

However, ready assembling with the jet-providing pipe 21 of additional shields or even changing of the length dimensions of the shields, is more readily possible in the form of the split ring 25, wherein the termini are a pair of parallel outwardly extending flanges 29 perforated to have extend therethrough bolt 30 to be engaged by wing nut 31. Accordingly, slackening of this wing nut 31, as slackening of the set screw 28, releases this clamp sleeve for adjustment longitudinally of the pipe 21 and then setting up of the wing nut 31 effects the holding in a position to shield a desired number and location of the jets 22 against escape of gas fuel of whatever type adopted.

What is claimed and it is desired to secure by Letters Patent is:

1. In a printing press, delivery means embodying a frame for transferring a printed sheet therefrom, a plurality of conveyor tapes independently transversely adjustable on said frame, bracket means mounted on and slidably adjustable along said frame, a burner carried by bracket means and extending transversely of said tapes and therebelow, said burner providing a series of upwardly directed ports, shields carried on said burner to close the ports below each respective tape and thereby making the burner discontinuous in its transverse extent, said shields being shiftable along the burner corresponding to the independently adjusted tape positions, and means clamping said shields to the burner in their respective adjusted positions.

2. In a printing press, delivery means embodying a frame for transferring a printed sheet

therefrom to a depository, a plurality of conveyor tapes independently transversely adjustable on said frame, a slide engaging said frame, a burner carried by said slide extending transversely of said tapes and therebelow, said burner providing a series of upwardly directed ports, shields carried on said burner to cover the ports below each respective tape, said shields being shiftable along the burner corresponding to the independently adjusted tape positions and embodying burner embracing sleeves, rings fixed with said sleeves, and means carried by said rings to positively clamp said sleeves in adjusted position.

3. In a burner of the class described, said burner having a series of ports, a shield for closing a portion of said ports embodying a split sleeve embracing the burner, a ring surrounding the sleeve, means fixing said ring with said sleeve, and means carried by the ring to clamp said sleeve against transverse shifting on said burner.

4. In a printing press, delivery means embodying a frame for transferring a printed sheet therefrom to a depository, a plurality of conveyor tapes independently transversely adjustable on said frame, an operator's station on one side of said frame, a slide carried by said frame, a duct carried by said frame extending transversely of said tapes, a duct extending to said transversely extending duct and connected thereto at the opposite side of said frame from the operator station, a burner carried by said slide extending transversely of said tapes and therebelow, said burner having a connecting duct therefrom to the first mentioned transversely extending duct, and a valve in said latter duct adjacent the operator's station.
